UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

LINE FINDER FOR TYPEWRITERS.

Application filed February 28, 1920. Serial No. 361,922.

To all whom it may concern:

Be it known that I, OTTO A. HOKANSON, a citizen of the United States, residing at Woodstock, in the county of McHenry and State of Illinois, have invented certain new and useful Improvements in Line Finders for Typewriters, of which the following is a specification.

This invention relates to typewriter construction, and especially to a mounting for that portion of a typewriter usually known as the line finder and has for its object the provision of mechanism of the class mentioned which shall be of improved construction and operation.

This invention is exemplified in the combination and arrangement of parts shown in the accompanying drawing and described in the following specification, and it is more particularly pointed out in the appended claims.

In the drawing—

Fig. 1 is a fragmentary transverse sectional view of a portion of a typewriter showing one embodiment of the present invention; and

Fig. 2 is an enlarged section on line 2—2 of Fig. 1.

Fig. 3 is a fragmentary elevation looking from the left in Fig. 1.

In Fig. 1 of the drawing the numeral 10 designates a typewriter platen supported on a typewriter frame 11 and 12 is a line finder arranged to bear against the platen 10 and having a construction of the general character of that shown and described in my prior application, Serial No. 225,949, filed April 1, 1918. As explained in the prior application referred to, the line finder 12 is provided with a horizontally arranged straight edge 13 which indicates the level of the printing line relative to the platen 10 and the face of the finder adjacent the edge 13 is provided with marks or graduations to indicate the lateral position of the letters formed by the type. An opening is provided through the central portion of the line finder adjacent the edge 13 to permit the type to strike the surface of the platen 10 and to indicate the printing position. The line finder 13 is provided with a pair of rearwardly bent ears 14 which are pivotally mounted at 15 on bell cranks 16. The bell cranks 16, as shown in Fig. 2, are

rigidly secured to a rock shaft 17 having flat portions 18 for preventing rotation of the bell cranks relative to the shaft. The shaft 17 is supported for oscillation by a bracket 19 having rearwardly projecting arms 20 and secured by screws 21 to a bar 22 which forms a part of the typewriter frame. The bracket arms 20 are shown in section in Fig. 2 and the one at the left of the figure carries a pivot stud 23 which enters an opening 24 in the end of the shaft 17 and is provided with a rounded bearing 25 to permit oscillation of the shaft 17 about the stud 23 without danger of binding between the shaft and stud in case the shaft is not in absolute alignment with the stud. The stud 23 is formed integral with a screw 26 which passes through the opening in the bracket arm 20 and which is firmly held in place in the bracket arm by a nut 27 threaded on the screw 26. The opposite end of the shaft 17 is provided with an integral screw 28 on which is threaded a bushing 29 having a bearing shoulder 30 journaled in the bracket arm 20. A nut 31 is carried by a threaded portion 32 of the bushing 29 which projects beyond the outer face of the bearing bracket 20. The nut 31 engages the shoulder 30 to prevent binding against the bracket arm 20 in order to permit of easy oscillation of the bushing 29 in the bracket arm. A lock nut 33 is threaded onto the end of the screw 28 to hold the bushing 29 in fixed position on the screw 28. The nut 33 is so proportioned that it projects beyond the end of the screw 28 and is provided with a screw-driver slot 34.

It will be apparent that this construction permits oscillation of the shaft 17 in the bracket arms 20 in order to raise and lower the line finder 12 relative to the typewriter frame. The vertical movement of the line finder 12 is desirable in order to retain the line finder in proper position relative to the platen 10 when the platen is shifted vertically to change from one case letters to another. In order that the vertical shifting of the line finder shall occur synchronously with the movement of the platen the bell crank 16 is provided with a link 35 having one end pivotally connected at 36 and having the other end connected with the mechanism for shifting the platen. Any suitable connection between the link 35 and the platen

shifting mechanism may be employed, one connection for such purpose being shown in my prior application referred to above. The length of the link 35 may be adjusted by 5 screws 37 and slots 38 which will permit of adjustment of the height of the line finder 12 to accurately position the line finder relative to the platen 10. A spring tongue 39 is connected with the line finder 12 and bears 10 against a portion of the platen shifting mechanism for resiliently pressing the line finder against the platen.

When a machine is first assembled and sometimes after the machine has been in operation it is desirable to be able to shift the line finder 12 laterally to accurately adjust the central opening therein relative to the printing position and also to locate the graduations on the line finder to accurately indicate the letter positions in a lateral direction 15 along the platen. In the present construction this lateral adjustment of the line finder may be accomplished by loosening the lock nut 33 and rotating the bushing 29 on the screw 28. It will be apparent that rotation 20 of the bushing 29 relative to the screw 28 will shift the screw 28 and the shaft 17 connected therewith in the direction of the axis of the screw and thus the line finder 12 may 25 be very accurately adjusted in a lateral direction. When the proper position of the line finder is secured it is only necessary to tighten the lock nut 33 which will prevent further rotation of the bushing 29 on the screw 28 and the line finder will then be permanently secured in its proper position. Such adjustment is very easily accomplished 30 at any time and may be very accurately made because of the fact that it is produced by a 35 screw-threaded arrangement.

I claim:—

1. In a typewriter, a platen, a line finder for indicating the position of the printing line relative to said platen, means for adjusting said line finder relative to said platen in a direction transverse to said printing line, and means for adjusting said line finder relative to said platen in a direction parallel to said printing line.
2. In a typewriter, a platen, a line finder for said platen, means for shifting said line finder to maintain said line finder in fixed position relative to said platen for different positions of said platen, and means for adjusting said shifting means to accurately position said line finder relative to said platen.
3. In a typewriter, a platen, a line finder for indicating the position of the printing line relative to said platen, means for shifting said line finder to maintain said line finder and platen in proper position relative to one another for various positions of said platen, means for adjusting said line finder relative to said platen in the direction of said shifting movement, and means for ad-

justing said line finder in a direction transverse to said shifting movement.

4. In a typewriter, a line finder, a pivotal support for said line finder comprising a rock shaft, and a bearing for one end of said shaft arranged to permit angular movement of the axis of said shaft without causing said bearing to bind.

5. A line finder for typewriters having a support, a pivot at one end of said support 75 on which said support is mounted for free pivotal and horizontal movement, means at the other end of said support for adjusting said line finder in the direction of the axis 80 of said pivotal support, and means for locking said line finder in various adjusted positions, said line finder having a line indicator the indicating edge of which extends in the direction of the printing line.

6. A line finder for typewriters comprising a pivotal support having a bearing at one end thereof arranged to permit oscillation 85 of said line finder about the axis of said pivotal support in various angular positions of said axis, and means for shifting said line finder in the direction of the axis of said pivotal support.

7. A line finder for typewriters comprising a pivotal support having a bearing at one end thereof arranged to permit oscillation 95 of said line finder about the axis of said pivot for various angular positions of said axis and to permit said line finder to move in the direction of said axis, a bearing for the opposite end of said pivotal support, and means connected with said last-mentioned bearing for shifting said pivotal support in the direction of said axis.

8. A line finder for typewriters comprising a supporting shaft having an elongated opening in one end thereof extending in the direction of the axis of said shaft, a rounded bearing for said shaft positioned in said opening, a threaded extension on the opposite end of said shaft, a bushing adjustably 105 mounted on said threaded extension, and a pivotal support for said bushing.

9. A line finder for typewriters comprising a supporting shaft, a bearing for one end of said shaft arranged to permit said 115 shaft to move in the direction of the axis thereof relative to said bearing, a threaded member carried by the opposite end of said shaft, a bushing threaded on said member and movable relative thereto to shift said 120 shaft in the direction of the axis thereof, and a pivotal support for said bushing.

10. A line finder for typewriters comprising a supporting shaft having a longitudinally extending opening in one end thereof, 125 a pivot stud having a rounded end extending into said opening to permit oscillation of said shaft about its axis in various angular positions of said axis and to permit movement of said shaft in the direction of the 130

axis thereof, a threaded member carried by movement of said shaft in the direction of the opposite end of said shaft, a bushing said axis when said bushing is rotated about threaded on said member, a lock nut for said threaded member. In testimony whereof I have signed my holding said bushing in fixed position on 10 name to this specification on this 24th day 5 said threaded member, and a pivotal support of February, A. D. 1920. OTTO A. HOKANSON. for said bushing arranged to permit oscillation of said shaft about its axis and to cause
